UNITED STATES PATENT OFFICE.

ARNO BOERNER, OF DRESDEN, GERMANY, ASSIGNOR OF TEN PER CENT TO ROBERT SUCZEK, OF CZECHO-SLOVAKIA.

MEANS FOR OVERCOMING FLUID FRICTION.

Application filed April 30, 1927, Serial No. 187,833, and in Germany June 12, 1926.

The resistances which arise as frontal and skin resistances when bodies are moving through currents of liquid and air are well known, and can be ascertained experimentally in water tanks, wind passages and the like, for example, and also calculated. In connection with these resistances the constitution and the shape of the body naturally play a considerable part.

Hitherto, in this branch of technology, success has not been attained in propelling bodies by motor means or the like with such small forces as animals, birds, and fishes require for overcoming these flow resistances. In their case the flow itself must serve as a source of power for overcoming the resistances. For example, I have ascertained that the forward movement of a fish is chiefly effected by the water pumping mechanism of its gills, and the fins and tail members are only to be regarded as auxiliaries. Upon this discovery the present invention is based.

The invention consists in separating the body from the currents of liquid or air, as the case may be, by interposing masses of liquid or air automatically moved in a direction opposite to the direction of the forward movement of the body, which may be a ship, an airship, a flying machine or the like.

The interposed layer may consist of the actual fluid which occasions the obstructing currents, as this fluid (liquid or air) may be led through passages into the moving body, and subsequently expelled again through nozzle-like apertures in the sides of the body.

This measure may be assisted by accelerating the fluid, which is admitted through the apertures, and discharged through the nozzles, and which therefore surrounds the body like a mantle, by means of mechanical appliances such as pumps, turbines, propellers or the like during its passage from the inlet apertures to the discharge apertures.

In order to surround the moving body with a mantle of flowing liquid and therefore to eliminate current resistances, the inlet and outlet passages are distributed over the entire external surface of the body. Thus in the case of a ship for example, these passages are arranged not only on the sides, but also on the keel walls; and in the case of an airship for example they are likewise arranged not only laterally, but also at the top and bottom of the airship.

The success attained is increased if the sur-

faces of the body in contact with the interposed flowing medium are also equipped with projections or ridges, in such a manner that by means of scale-like protuberances or the like, which rise out of the surface in the direction of forward movement, and then fall away more or less suddenly, the formation of eddies in the flowing medium surrounding the body is promoted, the said ridges or projections offering no resistance to the flow of fluid in the direction of travel, but having properties which cause them to offer great resistance in the opposite direction.

It is further possible, by means of the masses of liquid or air expelled through the nozzles, to effect the steering of the body, by throttling or entirely closing certain of the nozzle passages by means of valves or the like. This method of steering is particularly advantageous for airships, if the currents of air discharged from the bottom and top surfaces are alternately strengthened or weakened for the purpose of vertical steering.

The ridging already mentioned on the surfaces of the body must under some circumstances be very finely arranged, and may in this case be produced by profile rollers on the wooden, metallic or fabric sides.

The invention is illustrated by way of example in the accompanying drawings, where-

in

Figures 1 and 2 show in side elevation and in a view from below a steamship.

Figure 3 is a detail view,

Figures 4 and 5 show a side elevation and a plan of an airship, while

Figure 6 shows an aeroplane in side elevation, and Figure 7 the supporting plane thereof in perspective.

In the case of the steamship illustrated in Figures 1 and 2, the side walls and the keel walls, the latter completely and the former partially, come into contact with the water, while the upper parts of the side walls come into contact with the air.

According to the invention in the side walls, both in the part which is in the air and in the part which is immersed in water, inlet apertures *a* and *b* are provided for air and water respectively and on the keel surface inlet apertures *c* for water. Through these apertures, which, in the case of the constructional example illustrated are located at the bow of the ship, the fluid entering passes into passages which are indicated by dotted lines

- and in these passages is accelerated by propellers indicated at *d*, after which it is expelled again through nozzle apertures *e* provided in the sides and in the keel walls.
- 5 The medium thus accelerated surrounds the sides of the ship in question like a mantle and thereby eliminates direct contact of the fluids through which the ship is moving (air or water), and at the same time also eliminates the frictional resistances which would otherwise result from direct contact. In addition to this the accelerated fluid materially assists the easy forward movement of the ship's hull.
- 15 Inlet apertures for air and water may of course also be arranged one behind the other, having regard to the direction of forward movement, in various places on the sides of the ship in question, for the purpose of making the envelopment of the vessel as uniform as possible from bow to stern.

Now the walls in question are provided with ridges or projections. Figure 3 for example shows diagrammatically a construction of such ridges or projections produced by scale-like attachments *f* to the sides of the ship, these attachments being arranged in series and rising gradually out of the ship's wall and then suddenly falling away, so that 25 they offer no resistance to the flowing medium accruing, but behind the point where they fall away they produce eddies in the fluid, which materially assist the impulsive action, so that the vessel is driven forwards.

35 In the case of the airship illustrated in Figures 4 and 5, we again find the air inlet apertures *a*, and likewise the discharge nozzle apertures *e*, and the propellers *d* inserted in the passage. Here again the entire envelope of 40 the airship is equipped with the ridges or projections mentioned. In the case of the airship envelope, which in its entirety is immersed in the fluid, consisting of air, the air inlet apertures may of course be distributed 45 all over the envelope, and may thus for example be arranged not only on the side surfaces, but also at the top and bottom. The arranging of such apertures on the top and bottom surfaces is particularly valuable in the case 50 of airships, as the steering in a vertical direction can be effected by the aid of the said devices.

In order to render this possible, valves are interposed in the passages leaving the inlet 55 apertures, and these valves enable the passages to be throttled or even completely closed.

60 In the case of the constructional example according to Figure 6, it is shown that the body of an aeroplane may also be constructed with the air inlet apertures *a*, outlet nozzles *e*, and so forth, as can also the supporting planes.

What I claim is:—

1. In combination with a body moving in a medium, means for overcoming the frontal and skin resistance caused by the forward movement of the body, comprising a plurality of conduits in said body, said body having a plurality of inlet openings in the forward part of said body adapted to permit the medium to enter and a plurality of outlet openings in its outer surface arranged behind said inlets, said conduits connecting said inlets and said outlets, a plurality of projections on the outer surface of said body, said projections extending outward in the direction of the forward movement of said body and gradually tapering inwardly toward the rearward direction of the body, and means disposed in said conduits for accelerating and discharging the medium through the outlet openings, thereby causing it to flow along the outer surface of the body. 65

2. In combination with a body moving in a fluid, means for overcoming the frontal and skin resistance caused by the forward movement of the body, comprising a plurality of conduits in said body, said body having a plurality of inlet openings in the forward part of said body adapted to permit the fluid to enter and a plurality of outlet openings in its outer surface arranged behind said inlets, said conduits connecting said inlets and said outlets, a plurality of projections on the outer surface of said body, said projections extending outward in the direction of the forward movement of said body and gradually tapering inwardly toward the rearward direction of the body, and means disposed in said conduits for accelerating and discharging the fluid through the outlet openings thereby causing it to flow along the outer surface of the body. 90

3. In combination with a ship moving through a medium, means for overcoming the frontal and skin resistance caused by the forward movement of the ship, comprising a plurality of conduits in the body of said ship, the bow of said ship having a plurality of inlet openings adapted to permit the medium to enter and a plurality of discharge openings in its outer surface disposed behind said inlet openings, said conduits connecting said inlet openings and said discharge openings, a plurality of projections on the outer surface of the body of said ship adapted to produce eddies in the medium flowing along the sides of the body of the ship and effect a resistance in the opposite direction of travel of the ship, and means disposed in said conduits for accelerating and discharging the medium through the discharge openings. 100

110 In testimony whereof I have signed my name to this specification.

ARNO BOERNER.
